UNITED STATES PATENT OFFICE.

PHILIP C. WENTWORTH, OF PROVIDENCE, RHODE ISLAND.

MACHINE FOR AND METHOD OF FORMING RING TRAVELERS.

Application filed October 27, 1921, Serial No. 510,919. Renewed June 21, 1924.

To all whom it may concern:

Be it known that I, PHILIP C. WENTWORTH, a citizen of the United States, residing at Providence, county of Providence, State of Rhode Island, have invented certain new and useful Improvements in Machines for and Methods of Forming Ring Travelers, of which the following is a specification.

10 This invention relates to a machine for and method of forming the ring travelers illustrated in the patent to Philip C. Wentworth, No. 1,415,069, granted May 9, 1922, to which reference is made as indicating the

15 particular type of traveler involved herein.

The ring traveler illustrated in said Wentworth patent is of standard type, but is provided through its bow portion with a longitudinally disposed ventilating slot 20 which permits a draft through the traveler effective to prevent the accumulation of lint thereon.

The production of such travelers in commercial quantities and in the several standard sizes and thicknesses which the trade requires is complicated by several factors characteristic of both the traveler itself and of the existing equipment heretofore used to produce the old style traveler.

30 In the first place, it is highly desirable to utilize existing manufacturing equipment to produce the new type of traveler, because of the heavy investment which such existing equipment represents, and because of the 35 generally satisfactory character of such equipment.

The adaptation of such equipment, however, to the production of the new type traveler in all the varying sizes and thicknesses thereof, presents several difficulties. It is of the utmost importance that the ventilating slot be located in each traveler, and in each size of traveler, at exactly the center of the traveler bow, since any variation in 45 the location of such slot will destroy the balance of the traveler. The slot cutting mechanism and the stock feed, cutting and bending mechanisms must therefore not only operate in properly timed relation, but 50 must be capable of such relative adjustment that the slots will be accurately cut in travelers of a different size from that which the machine had been previously forming.

To the end therefore of adapting such 55 existing equipment to the production of the new type traveler in all the usual sizes and

thicknesses of the old type traveler, I have devised my present invention.

The construction and operation of my invention, together with a selected embodiment which well illustrates the principles involved and is in itself a form which I have found satisfactory under actual working conditions, are described and shown in the accompanying specification and drawings, and the characteristic features of novelty are particularly pointed out in the appended claims.

Throughout the specification and drawings, like reference characters are correspondingly employed and in the drawings:

Figure 1 is a front view of a ring traveler forming machine equipped in accordance with my invention.

Fig. 2 is a rear view thereof.

Fig. 3 is a plan view.

Fig. 4 is an end view from the right of Fig. 1.

Figs. 5, 5^a and 5^b are diagrams illustrating the action of the stock punching, feed, cutting and bending mechanisms.

Fig. 6 is a section showing the reciprocating anvil over which the stock is cut and bent.

Figs. 7 to 16 inclusive are detail views of the punch and die mechanism for cutting the slot in the ring traveler bow, and

Fig. 17 is a diagrammatic illustration comparative of the relation of stop and punch for two sizes of traveler.

I have indicated at 1 a suitable frame work and at 2 a cam shaft journaled longitudinally thereof and provided at one end with a fast pulley 3 and a loose pulley 4 over which a driving belt 5 is adapted to be shifted to connect and disconnect the drive.

The stock S is intermittently fed in strip form by a pair of opposed, oppositely revolving feed rolls 9 between which the strip is gripped. In advance of said feed rolls 100 is a punch and die mechanism 8 for cutting the slots S¹ at definitely spaced intervals in the strip so that each slot comes exactly at the center of the traveler bow when the traveler blanks B are cut along the dotted 105 lines, Fig. 17, and the blanks bent to ring traveler form, as indicated in Figs. 5, 5^a, 5^b and 6.

From the feed rolls 9, the slot provided strip S passes along a guideway 10 until 110 its free end contacts a stop 100 adjustably mounted in the line of feed of the strip.

Mounted in advance of the stop 100 is a horizontally reciprocating anvil 11 over which the stock is severed by the cooperation of a vertically reciprocating swaging mechanism 50 and stationary cutters 60. The individual blanks are then bent to ring traveler form by a pair of oppositely disposed reciprocating bending dogs 70.

The punch and die mechanism 8 for slotting the stock is detailed in Figs. 7 to 15 inclusive. Referring to these figures I have indicated at 15 a bracket which is attached to one of the standards of the frame work 1 and is provided in its horizontal portion 15' with a slideway 16 along which is adjustable by means of a feed screw 17 a casting 18. The slide 18 has a vertical extension 19 constituting a slideway for the vertically reciprocating punch block 20 of the punch and die mechanism and beyond said slideway is offset and extended upwardly, through which the cam shaft 2 extends.

Fast within a recess at the lower end of the punch block 20 is a punch 21. The punch block is reciprocated in its slideway from the cam shaft 2 by a cam 22 thereon operating against the head 23 of a connecting rod 24 to which the upper end of the punch block is fastened.

Below the guideway 19 the slide casting 18 is recessed as shown in Fig. 16 to receive a die block 25' which is fastened to the casting, as indicated at 25². The block 25' has a central chip-clearance slot 25^a and adjacent said slot is formed with spaced longitudinally extending lugs 25^b providing a guideway for the die 25^c. (Figs. 11, 12 and 13.)

The die 25^c is sectional, consisting of two sections detachably connected to each other by the pins 25^d. The die sections are each centrally cut away along their opposing edges to provide a slot 25^e adapted to align with the punch 21 and with the chip clearance slot 25^a of the block 25'. The die is formed to fit the guideway 25^b and is adjustable longitudinally therealong, the adjustment being held by a set screw 25^f. As here shown, one face of one of the die sections is beveled as indicated at 25^g to fit correspondingly beveled face of one of the lugs 25^b constituting the guideway for said die.

Surmounting the die is a pair of spaced guide strips 26 constituting a guideway 27 (Figs. 10 and 16) for the stock S. The opposed edges of each guide strip 26 are centrally cleared away as indicated at 28 (Fig. 10) to provide a slot alined with the punch 21 and with the opening 25^e of the die 25^c.

The guide strips 26 are adjustably mounted in an angularly-formed holder 25 (Fig. 9) which is clamped within the recess of the slide casting 18 by clamping screws 250.

65 The guide strips 26 have downwardly ex-

tending lugs 26' which enter transversely disposed slots 26^a in the divided bottom wall of the holder 25. Set through the holder and guide strips is a plurality of adjusting screws 26^b by means of which the strips 26 70 may be relatively adjusted. (Figs. 15 and 16.)

The screw 17 permits the slide 18 carrying the punch and die to be moved towards and from the anvil 11 whereby to locate the 75 slots S¹ formed in the strip S by the punch exactly at the center of the bow of the traveler when the strip S is cut into blanks B by the cutters 50 and 60 and the blanks 80 formed over the anvil.

The feed rolls 9 are intermittently actuated from the cam shaft 2 by a cam 30 on said shaft which actuates a cam lever 31 which is pivoted between its ends at 32 to the frame work of the machine and is under spring control as indicated at 44, Fig. 2. The lower end of the lever 31 is provided with a gear segment 33 meshing with a pinion 34 on a stub shaft 35. (Fig. 2.) The rotation of the stub shaft 35 is transmitted to the feed rolls by a gear 36 on said shaft which meshes with a gear 37 on the upper feed roll shaft. The gear 37 meshes with a gear 38 on the lower feed roll shaft, (Fig. 2), whereby to rotate the feed rolls 95 in unison and in opposite directions.

Fast on the stub shaft 35 is a ratchet wheel 39 with which cooperates a pair of pawls 40 pivoted in recesses cut in the outer face of the gear 36.

100 The lower feed roll shaft is mounted in a floating bearing and is normally urged towards the upper feed roll shaft by a coil spring 41. (See Fig. 1.)

The swaging mechanism comprises a 105 finger 50 and a pair of swages 51 disposed one on each side of the finger 50. The finger and swages are mounted in a slide block 52 (Fig. 1) which reciprocates vertically in a slideway 63 mounted on the framework of 110 the machine, being actuated from a cam 64 on the cam shaft 2.

The anvil 11 is reciprocated horizontally across and slightly below the path of the stock feed by a cam 61 on the cam shaft 2, 115 which actuates a cam lever 62 that is pivoted at 63 to the framework 1 (see Fig. 2) and through the links 64' reciprocates the plunger 65 which carries the anvil. Said plunger 65 is suitably guided in a guideway 66 (Fig. 6) extending from front to rear of the framework.

As the finger 50 descends the anvil is advanced so that the finger holds the stock on the anvil (Fig. 5) while the swages 51 move 125 past the anvil and cut the stock over the stationary cutters 60 (Fig. 5^a). At this time, a pair of oppositely disposed bending dogs 70 mounted below the cutters 60 are advanced towards the anvil to bend in the 130

extremities of the blank B, thereby forming the horns of the traveler (Fig. 5^b).

The bending dogs 70 are adjustably mounted at 71 in suitable blocks 72 and are 5 actuated from the cam shaft 2 through a pair of cam levers 73 (Fig. 2) which are pivoted between their ends at 74 to the framework and at their upper ends have cam rolls 75 on the cam shaft. The cam 10 levers 73 on either side of their pivots 74 are under spring control as indicated at 78 and 79, Fig. 2.

After the traveler blank is cut and formed, the anvil 11 is withdrawn, stripping the formed traveler from the anvil and allowing it to fall, as indicated in Fig. 6, to the bottom of the machine.

When the parts are adjusted to cut travelers of the size and length indicated at AA 20 in the diagram of Fig. 17, there is of course a determinate number of traveler blanks between the slotting station 8 and the cutting and forming station 50—70. When, however, it is desired to cut travelers of a 25 different size and length, as indicated at BB, Fig. 17, the number of blanks between the slotting and cutting and forming stations will be changed owing to the increase or decrease (as the case may be) in the length of 30 the new blanks. In order to take care of this variation in both number and length of the intervening blanks, so that the slots S will be located exactly in the center of the traveler bow for the new size of traveler, the 35 entire slotting station 8 is adjusted by means of the feed screw 17 towards or from the relatively fixed cutting and bending station until the proper relative spacing is found for the particular blank length to be cut.

40 Although I have described and illustrated my invention in its adaptation to the formation of a ring traveler of the "horseshoe" type, comprising a pair of terminal horns and an intermediate connecting bow, it will 45 be understood that such treatment is purely illustrative and in no way limiting, and that the vertical type of ring traveler known as a twister traveler and shown in my prior Patent No. 1,415,072, granted May 9, 1922, 50 may also be produced upon my machine. The term "ring traveler" as used herein, is therefore to be construed broadly as meaning any traveler, whether for ring spinning or twisting which travels about a ring.

55 Various modifications in the form and construction of my device may obviously be resorted to without departing from the spirit of my invention, if within the limits of the appended claims.

60 What I therefore claim and desire to secure by Letters Patent is:

1. In a ring traveler machine, the combination with stock feed mechanism and bending and cutting mechanism, of slot-cutting 65 mechanism operating simultaneously with

said bending and cutting mechanism to cut a slot in the stock at the region of the bow of the traveler when formed, a stop for the stock and means whereby said slot-cutting mechanism and said stop may be adjusted 70 towards and from said bending and cutting mechanism.

2. In a ring traveler machine, the combination with stock feed mechanism and bending and cutting mechanism, of slot-cutting 75 mechanism operating simultaneously with said bending and cutting mechanism to cut a slot in the stock at the region of the bow of the traveler when formed, and means whereby said slot-cutting mechanism may 80 be adjusted towards and from said bending and cutting mechanism.

3. In a ring traveler machine, the combination with stock feed mechanism and bending and cutting mechanism, of slot-cutting 85 mechanism to cut a slot in the stock at the region of the bow of the traveler when formed, and means whereby said slot-cutting mechanism may be adjusted towards and from said bending and cutting mechanism. 90

4. In a ring traveler machine, a cam shaft, stock feed, slot-cutting and bending and cutting off mechanisms, cams on said shaft for actuating said several mechanisms in properly timed relation, and means whereby said 95 slot-cutting mechanism may be adjusted towards and from said bending and cutting off mechanism.

5. In a ring traveler machine, a cam shaft, stock feed, slot-cutting and bending and cutting off mechanisms, cams on said shaft for 100 actuating the slot-cutting and stock bending mechanism operating simultaneously, and means whereby said slot-cutting mechanism may be adjusted towards and from said bending and cutting off mechanism.

6. In a ring traveler machine, a stock feed mechanism, a bending and cutting off station at the end of the path of the stock feed, and a slot-cutting station in advance of said 110 stock feed mechanism, and effective to cut a slot in the stock at the region of the bow of the traveler when formed, at said bending and cutting off station, and means for operating the bending and cutting off mechanism and the slot-cutting mechanism simultaneously.

7. In a ring traveler machine, an intermittently acting stock feed mechanism, a bending and cutting off station at the end 120 of the path of the stock feed, including an adjustable stop, and an adjustable slot-cutting station in advance of said bending and cutting off station, and effective to cut a slot in the stock at the point which will 125 become the bow of the traveler when formed at said bending and cutting off station.

8. In a ring traveler machine, an intermittently acting stock feed mechanism, a bending and cutting off station at the end 130

of the path of the stock feed, including an adjustable stop, and an adjustable slot-cutting station in advance of said bending and cutting off station, and effective to cut 5 a slot in the stock at the point which will become the bow of the traveler when formed at said bending and cutting off station, and means for operating the bending and cutting off mechanism and the slot cutting mechanism simultaneously.

9. In a ring traveler machine, an adjustable stop, an intermittently acting stock feed mechanism adapted to feed said stock against said stop, a bending and cutting off station, and an adjustable slot-cutting station in advance of said bending and cutting off station, and effective to cut a slot 15 in the stock at a point which will become the bow of the traveler when formed at said bending and cutting off station.

10. In a ring traveler machine, an adjustable stop, an intermittently acting stock feed mechanism adapted to feed said stock against said stop, a bending and cutting off station, and an adjustable slot-cutting station in advance of said bending and cutting off station, and effective to cut a slot in the stock at a point which will become the bow of the traveler when formed at said bending and cutting off station.

11. In a ring traveler machine an intermittently effective stock feed mechanism, a bending and cutting off station at the end of the path of the stock feed, and a metal removing station in advance of said stock feed mechanism and effective to remove a portion of the stock at a point which will become the bow of the traveler when the stock is cut off and bent to traveler form at said bending and cutting off station.

12. In a ring traveler machine, an intermittently effective stock feed mechanism,

a bending and cutting off station at the end of the path of the stock feed, and a metal removing station in advance of said bending and cutting off station and effective to remove a portion of the stock at a point 50 which will become the bow of the traveler when the stock is cut off and bent to traveler form at said bending and cutting off station, and means whereby said metal removing station may be adjusted towards and from said 55 bending and cutting off station.

13. In a ring traveler machine, the combination with an intermittently effective stock feed mechanism and stock bending and cutting off mechanisms, of a stock removing 60 mechanism operating in advance of said stock feed mechanism and effective to remove a portion of the stock at a point which will become the bow of the traveler when the stock is cut off and bent to traveler form 65 by said bending and cutting off mechanisms, and means for operating said stock removing mechanism on the non-feeding phase of said stock feed mechanism, said stock removing mechanism being ineffective upon 70 the feeding phase of said stock feed mechanism.

14. The method of producing a ring traveler, consisting in intermittently feeding a continuous strip of stock, in intermittently bringing a metal remover against the stock in advance of the stock feed mechanism on the non-feeding phase of the stock feed mechanism to remove definite portions 80 of the stock at predetermined spaced intervals longitudinally of the strip, in severing the strip intermediate of said removed portions to form the traveler blank, and in bending the blank to form the traveler.

In testimony whereof I affix my signature 85 in presence of two witnesses.

PHILIP C. WENTWORTH.
